UNITED STATES PATENT OFFICE.

WILLIAM T. LAWING, OF OZARK, MISSOURI.

CULTIVATOR.

No. 829,973.

Specification of Letters Patent.

Patented Sept. 4, 1906.

Application filed October 23, 1905. Serial No. 283,957.

To all whom it may concern.

Be it known that I, WILLIAM T. LAWING, a citizen of the United States of America, residing at Ozark, in the county of Christian 5 and State of Missouri, have invented certain new and useful Improvements in Cultivators, of which the following is a specification.

This invention relates to plows, and more particularly to a one-horse sulky-cultivator 10 designed to work between two rows, utilizing one horse as a source of power for drawing the cultivator.

An object of this invention is to provide novel means for applying the draft-rigging 15 described in drawings as E, F, D, C, A, G, H, and S, complete to parts or any common cultivator making it a one-horse cultivator, means being provided to permit the ready 20 manipulation of the cultivator with relation to this draft-rigging.

Furthermore, an object of this invention is, as shown, to provide stay-chains connecting this draft-rigging and plow-beams in order 25 that undue movement of the cultivator may be prevented.

A still further object of this invention is to provide a sulky with novel means for attaching one horse thereto in front of the sulky and in the provision of novel means for ad- 30 justably connecting the cultivator to the sulky.

With the foregoing and other objects in view the invention consists in the details of construction and in the arrangement and 35 combination of parts to be hereinafter more fully set forth and claimed.

In describing the invention in detail reference will be had to the accompanying drawings, forming part of this specification, where- 40 in like characters denote corresponding parts in both views, in which—

Figure 1 is a plan view of the cultivator embodying the invention. Fig. 2 is a side elevation thereof.

45 In the drawings, A denotes an ordinary axle on which may be fitted any common cultivator-wheel axle supported by the ground-wheel B. Beams C are attached to the axle and have their outer ends converging 50 and contacting with a short tongue D, to

which the swingletree E is connected in any suitable manner through the medium of a link F. A clevis G is provided at each side of the sulky and is secured to the beams C and axle A through the medium of the bolt 55 H, by which the several parts are clamped together. The plow-beams I from any ordinary cultivator are connected to the clevises G, it being understood that the bolts K are provided for connecting the straps J and 60 clevises G. The position of the beams may be adjusted through the medium of the apertures L' in the clevises, though ordinarily it would be desirable to have the beams approximately on a plane with the beams C. 65

The cross beam or bar L is attached to the plow-beam by means of the clamps M, and said cross beam or bar has a series of shovels N connected to it, using any ordinary cultivator beam, plows, and handles. As the 70 specific construction of the plow-beam, cross beam or bar, the handles and the shovels, and means for attaching them to the cross-bar forms no part of the present invention, they will not be described in detail; but the 75 plow beams, handles, shovels, &c., are shown in the drawings for the purpose of specifying how the ordinary plow-beams from a common cultivator are attached to this one-horse sulky to accomplish the end for which 80 this sulky is invented.

As a means for bracing the structure suitable stay-chains S extend from the axle to the plow-beams, said chains crossing each other intermediate their length. By this 85 means a flexible connection is made between the axle and the cultivator proper. The bolt on the end of the stay-chain at K', where the bolt goes through the axle, is a take-up bolt with threaded nuts controlling 90 the length of stay-chains S, making them longer or shorter, as may be required.

Having fully described my invention, what I claim as new, and desire to secure by Letters Patent, is—

95 In a cultivator of the character described, an axle, converging beams attached thereto, clevises carried by the axle, bolts passing through the clevises, axle and converging beams to hold said beams and clevises to the 100

axle, a swingletree connected to the converging beams, plow-beams adjustably secured to the clevises, stay-chains extending from the axle to the plow-beams, cross-bars attached to the beams, and cultivator-shovels carried by the cross-bars.

5 In testimony whereof I affix my signature,

in the presence of two witnesses, this 30th day of September, 1905.

WILLIAM T. LAWING.
